PROJECTION MUTOSCOPE

William Rabkin, New York, N. Y.

Application June 8, 1933, Serial No. 674,782

7 Claims. (Cl. 88—19)

This invention concerns a mutoscope, and more particularly such an apparatus in combination with and comprising projection apparatus.

As compared with cinematographic apparatus 5 in which diapositives are used, mutoscopes have a distinct advantage where a moving picture of short length is to be repeated very often, completely automatically, or in a switch or coin operated apparatus. This advantage is based primarily upon the simplicity, ruggedness and low 10 cost of installation and operation of mutoscope.

A particular point of advantage of a mutoscope is the greater durability of the picture to be exhibited when shown a great number of times.

15 On the other hand a disadvantage is the flickering caused by the flicking cards of the mutoscope; and another disadvantage of the moving picture produced by a mutoscope is its limited length; and still another disadvantage of the ordinary mutoscope is the limited size of the picture.

It has been an important object of this invention to overcome these disadvantages.

Further objects thereof provide a completely self-contained moving picture apparatus which 25 may operate continuously or may be remotely controlled, or which may be actuated by only a coin in the case where a coin freed mechanism is connected to the mutoscope, no manipulation whatever being necessary.

30 A further object is to make provisions for projecting a mutoscope picture at a larger scale onto a screen, and to provide for that purpose powerful means of illumination, without subjecting the mutoscope to excessive heat.

35 A further object of this invention is to provide on a projection mutoscope for interspersing a moving picture with still pictures at will, said still pictures being projected from a single card of the mutoscope for any preferred interval of 40 time. This greatly improves the visibility and clearness of still pictures interposed in moving pictures, permits them to be exposed for a preferred period of time, it enlarges the cycle of a mutoscope and greatly enhances its value for 45 advertising purposes.

This and other objects of this invention will be more fully explained from the following and are exemplarily illustrated in the mechanism of the accompanying drawings, in which

50 Fig. 1 shows the partly sectioned side elevation of an apparatus of my invention.

Fig. 2 shows a corresponding top view, part of the apparatus being sectioned away as indicated by a correspondingly identified dot-dashed line 55 in Fig. 1.

Fig. 3 illustrates in a detail view a stop-gap mechanism which may be used in connection with the apparatus of Figs. 1 and 2. It is partly schematic and comprises a wiring diagram.

Fig. 4 shows a top view corresponding to the 5 stop-gap detail view of Fig. 3.

Figs. 5 and 6 illustrate cards of mutoscope reels, in connection with means for adapting same for stop-gap operation.

Fig. 7 shows a detail view of the solenoid employed for the actuation of the projection mutoscope and a wiring diagram of the electrical devices.

Similar numerals refer to similar parts 15 throughout the various views.

The showing of Figs. 1 and 2 provides a housing H substantially enclosing the apparatus of my invention. Current is adduced to the housing through a cable C, said current providing full control of the apparatus if the apparatus is not 20 intermittently operated by coins, etc. The current supplied by the cable C may either be controlled at a remote point or on the apparatus directly, as indicated by switch S.

Aside from such current facilities, the apparatus opens to the outside of two other points only. First, through the screen B (made for instance, of frosted glass) which closes the front of the upper compartment U of the housing H. The said upper housing serves to accommodate 25 such parts of the apparatus which never need any attention, such as the rectifier and transformer which will be referred to hereinafter.

The lower part of the housing is preferably provided with full size doors D on both sides, which 35 close the housing when the locks N are actuated. One of said doors D is provided with an opening O which registers with a fan F mounted on the end of motor M. The opening O may be closed 40 by meshed wire 11, so that with the air, which is sucked in through the opening O for purposes of cooling the projecting lamps, is free of impurities or foreign matter before entering the housing.

The motor M may be provided with reducing 45 gearing built right onto it, as indicated at 12, so that the shaft 13, which issues from the motor into the machine frame 14 revolves at a reduced speed. Shaft 13 is connected by a flexible coupling or universal joint 15 to the worm shaft 16. 50 The worm 17 meshes with a gear 18 which idles upon a stud 19 mounted upon the frame 14. A downward extension 20 of frame 14 supports a lever 21 which carries at one end a wiper 22, lubricating the worm 17. The other end of lever 55

21 is weighted so as to retain the wiper 22 in contact with worm 17.

Near the end of worm shaft 16, flanges 23 are rotatably retained thereon. They are thrustwise 5 retained in fixed position on said shaft by a collar 24 forming part of shaft 16 and located between said flanges. The flanges 23 are connected with each other by pins or shoulder-rivets 25 and 26. By means of pin 25 one end of the hook 27 is fulcrumed upon flanges 23, the other end thereof being fulcrumed upon a pin 28 extending from the frame 14. The other pin 26 is vertically slidably accommodated in a slot 29 in the end of a rod 30, from which depends the core piece 31 of solenoid 15 32. The core piece 31 is shown in Fig. 7 to be pulled into the solenoid, upwardly, by excitation of windings of solenoid 32. When thus actuated, the rod 30, extending up from core 31 retains the worm shaft 16 in a raised position, in which the 20 worm 17 is in mesh with the gear 18, i. e., the position of Fig. 1.

When the current supply to the solenoid 32 is interrupted, the core piece 31 is released and drops gravitationally, the rod 30 sliding down on pin 26, 25 until said pin is engaged by the upper end of slot 29. By virtue of the momentum imparted to the core piece 31 and rod 30 by the said drop, the end of the slot 29 engaging upon pin 26 swings the flanges 23 around pin 25 in clockwise direction 30 (Fig. 7), so that the worm 17 is disengaged from gear 18. When the solenoid 32 is energized again, it pulls up the core piece 31, and thereby the rod 30, the lower end of slot 29 engages upon pin 26, and flanges 23 are swung in counter clockwise 35 direction in pin 25 until the worm shaft 16 resumes its position substantially on top of pin 25, in which the worm 17 is engaged upon gear 18.

It will be noted that I do not rely exclusively upon the action of the solenoid to retain the worm 40 17 in mesh with gear 18. The worm shaft 16 is vertically supported by pin 25, when in the position of Fig. 7. Whereas the solenoid is assisted by pin 25 in supporting the worm in mesh with the gear as long as the solenoid is energized, the 45 gravitational action of the core piece 31 swings the worm from the supporting pin 25, when the solenoid is energized.

The diagram of Fig. 7 shows the electrical wiring of the apparatus. The cables C adduce the 50 current through switch S and fuses A directly to the projection lamps L and the universal motor M, such a motor being chosen to allow the apparatus to be used on alternating current as well as on direct current. Current is also delivered 55 to the plug P (Fig. 2) which may be inserted into receptacle 33 or 34. A swivel cover 35 is shiftable from one to the other of said receptacles, which are respectively marked D. C. or A. C. The plug P is disconnected when a machine is delivered, 60 and the user must select between receptacles 33 and 34,—shifting cover 35 to the receptacle which is not in use,—before the whole electrical apparatus of the mutoscope is connected.

The solenoid 32 is provided with direct current 65 and "alternating current" windings which are superimposed upon each other and which actuate the core piece 31 in like manner, when suitably energized.

When the plug P is connected to receptacle 33, 70 the direct current winding of the solenoid 32 is energized, if the electric circuit is closed by the switch S. If the cable C supplies alternating current, plug P is inserted into receptacle 34, which feeds a transformer T and a rectifier R, 75 which then supplies direct current to the so-called

"alternating current" winding of the solenoid 32. In this manner it is possible to provide a solenoid actuating the core piece 31 without having hum or without overheating in the solenoid. The solenoid 32 is energized as long as the mutoscope is in 5 operation. Whether or not the motor is actuated during such time of operation, the worm is retained in mesh with the gear 18; but when the machine is not operating and the solenoid 32 has released shaft 16, so that worm 17 is out of mesh, 10 then the gear 18 and the mutoscope card wheel 36 can rotate at will and the latter may turn into a position where the cards are least pressed by thumb 48.

In order to operate the mutoscope in different 15 speeds, a variable rheosat W is connected in series with the motor M.

The lamps L are mounted to the left and to the right of the machine next to the mutoscope wheel 36. They are mounted in sockets 37 and 20 38, respectively, and the lamp L fitting socket 38 is omitted in Fig. 2 in order to show other parts located therebelow. A reflector 39 is provided in connection with each of the two lamps L, and serves to concentrate the strong light of each of 25 the lamps on the picture of the mutoscope wheel to be projected. But the reflector 39, mounted next to socket 38 is shown only in part in Fig. 2, the rest thereof being omitted for the same reasons that a lamp L is not shown in the said socket. 30

The reel 36 idles upon a shaft 40, which protrudes from the bracket 41. The shaft 40 has a pin 42 at its end which is inserted into a suitable opening in stud 19.

The gear 18 is retained endwise upon stud 19 35 and in alignment with the worm 17 by means of a segment 43, which is mounted upon the frame 14, and which slidably engages upon the other side of the gear 18, so that the position of said gear is fixed thrustwise. From the hub of the 40 mutoscope wheel 36 and from the gear 18 extend toward each other lugs 44 and 45 so that the gear 18 drives the mutoscope wheel 44, when rotated in counter clockwise direction (Fig. 1) against the action of thumb 48 which flicks the mutoscope 45 card.

The bracket 41 is retained upon the base of the housing H by means of a wing nut 46 engaged upon a stud 47 arising from said base. Since the bracket 41 is suitably slotted, it may be withdrawn in the direction of shaft 40, away from stand 14, when wing nut 46 is loosened up. The pin 42 on the end of the shaft 46 is thus withdrawn from the stud 19 and the shaft 40 is slid out of the mutoscope wheel 36, which then may 55 be withdrawn substantially at right angles to shaft 40 from between the protection lamps L, which are mounted upon both sides thereof.

Of course the lamps L do not register with the gap between the cards at the flicking gap when 60 the apparatus is not operated, because the cards pull the mutoscope wheel back in respect to the thumb 48, as soon as the worm 17 is released from gear 18, whereupon the mutoscope wheel finds a preferred position in relation to thumb 48, 65 at which the least pressure is exerted by said thumb upon the cards of the wheel.

The thumb 48 is rotatably mounted upon a rod 49 extending from a bracket 50 which is angularly adjustably mounted upon stand 14. A spring 70 51 is coiled up upon the rod 49 and is engaged upon the thumb 48 in such manner, that the end of the thumb is pressed in counter clockwise direction onto the cards of the mutoscope wheel as seen from Fig. 1. The angular play of the 75

thumb 48 is limited by a pin 52 engaged upon an angular sector 53 which is mounted upon stud 48 near the end thereof.

During operation the card wheel presses the thumb 48 into an extreme position in a clockwise direction at which the cards flick from thereunder. When the worm 17 releases gear 18 upon de-energization of the solenoid 32, the thumb 48 flops back under the tension of spring 51 into an extreme position in counter-clockwise direction, in which the thumb is disposed substantially radially in respect to the stud 19. The wheel 36 follows the said motion of the thumb by rotating in clockwise direction into a position where the last flicked card rests on top of the thumb.

The flicking of the cards during the operation of a machine takes place after a card has obtained a substantially horizontal position, in which it is substantially in the focus of the objective 54, which projects the picture or legend of said card as illuminated by the lamps L onto the inclined mirror 55 in the upper compartment U of the housing 8, and from there the enlarged picture is projected onto the screen B and is there exposed to visibility from the outside.

It will be noted that the lower end of the objective 54 just clears the normal diameter of the outside of the mutoscope. The flicked cards do not have to assume a position at right angles or more in respect to the card next to be flicked, because under the arrangement of this machine the objective permits a vision of the whole card next to be flicked, although the last-flicked card extends at an acute angle above the card next to be flicked. Under such an arrangement the cards do not have to be flicked through such great angles as formerly so that they are subjected to less wear and tear.

The horizontal disposition of the card to be projected serves best to allow a current of air to flow thereover and to take away the heat caused on the surface of said card by the two strong lamps L.

In order to conduct the circulation of the air as set up by fan F, over the periphery of the card wheel to the surface of the card to be projected, various auxiliary ducts may be used. In the drawings, a curved baffle 56 serves as a false ceiling directing the circulated air.

The objective 54 is provided with means for adjustment 57 so that it may be focused properly. The manner in which the said objective faces the mutoscope card which is held by the thumb in a projection position, and the manner in which the said objective is lowered below the top of the mutoscope wheel into the close proximity of the outer periphery of the cards may readily be seen from Fig. 3. The said figure also shows the last flicked card to be disposed at an acute angle with the card held by the thumb in a projection position, and the range of the objective extends underneath the said last-flicked card, although that range of the card, as covered by the objective, cannot be seen from a raised point above the mutoscope wheel.

The view of Fig. 3 also shows an arrangement for exposing some of the cards to view or for projecting same for a longer time than others. For that purpose some of the cards may be specially shaped, so that they engage the thumb in a different manner than the other cards and thus bring about a stopping of the motor, the releasing of a clutch on the drive, or simply causing a certain card to be held for a longer time in

the projection position, for a period determined by a timing mechanism.

In this particular instance I make use of an auxiliary finger 58, which exemplarily swivels upon rod 49, in a groove 59 centrally provided in thumb 48, said thumb extending around said finger in the shape of a fork. The back of the finger is shaped, so that its play around rod 49 is limited up- and downwardly by the inner part of the yoke connecting the two forked ends of the thumb. By gravity the finger 58 will normally rest at its lower end against the bottom of said yoke, and, since the tip 60 of the finger extends about as far or further away from rod 49 than the tip of thumb 48, at which the cards flick up from thereunderneath, notches 61 are provided in the cards, said notches clearing the said tip of finger 58.

But where a card is to be exposed to view for a longer period of time than the other, the notch is bridged, for instance a matting 62 is placed on top thereof, said matting being provided with a window through which may be seen the legend or picture on the card, which is to be exposed for a longer period of time (Fig. 5).

Whereas finger 58 normally depends into the groove provided by the notches in the various cards, it is engaged by the matting 62, which gaps said notches, and is slowly raised until its tip 60 comes into alignment with the tip of thumb 48. Now the matting is within the range of the objective and a mercury switch 63, which is mounted by means of a strap 64 on top of finger 58, has been tilted so far back, that the circuit 65 connected to said mercury switch to the left is broken, and the circuit 66 connected to said switch to the right is closed.

Circuit 65 controls in this instance a magnetic clutch Q which is interposed on the driving shaft 13 issuing from the motor M, between the reducing gear 12 and the stand 14. The clutch is exemplarily illustrated by a toothed clutch 67, which may be opened or closed by means of a forked lever 68 swivably mounted upon the stand and provided with a pole piece 69 at its lower end. The circuit 65 is supplied with current from the switch S in the manner of all the other electric parts of my apparatus. As long as the mercury switch 63 was tilted to the left, the electric magnet 70 was energized, so that the electro-magnetic clutch established the connection between shafts 13 and 16. But after the finger 58 has been lifted so far that the circuit of electric magnet 70 is opened, the clutch Q is released, and the motor runs empty, operating only the fan whereas the worm 17 retains gear 18 in a locked position, so that card seen through the matting 62 is continuously projected.

But in the meantime circuit 66 has been closed, which is connected to the current source in the manner of solenoid 32, and which comprises the solenoid 71. The solenoid 71 being thus excited, raises the core piece 72, and with it the stem 73, which slidably extends, by way of suitable packings 74, through cylinder 75. The cylinder 75 is shown as an example of a retarding mechanism and is filled with a suitable retarding fluid, which slowly oozes around the circumference of the piston 76 mounted on stem 73, as the said stem 70 and the pole piece 72 are lifted by the solenoid 71. In this manner the reaction of the core piece 72 in response to the energization of solenoid 71 is retarded, and a certain period of time lapses until pole piece 72 has been fully pulled into the sole-

noid and the stem has been raised to its highest position.

But before the said stem reaches its highest position it has raised a lever 76, the free end of which extends through a slot in said stem, until a mercury switch 77 mounted on said lever has been tilted into a closed position. When thus tilted, mercury switch 77 closes a circuit 78 which is connected in parallel into the circuit 65, said 10 circuit being closed by mercury switch 77 in the same manner, as it is closed by mercury switch 63 when the latter is tilted to the left. Since the closing of mercury switch 77 actuates the electro-magnet 70, the electro-magnet clutch Q is closed, 15 so that the mutoscope wheel is again connected with the motor M and is driven thereby.

The matting 62 flicks up from under the thumb 48 and the tip 60 of finger 58 (or only the latter if it is longer than the thumb and the matting 20 had previously escaped from the thumb), and the finger 58 drops back into the normal position in which it is shown in Fig. 3, ready to be actuated by the next matting which is brought up during the counter clockwise direction, the mercury 25 switch 63 returns to the position of Fig. 3, closing the magnetic clutch circuit in parallel with mercury switch 63 returns to the position of Fig. 3, closing the magnetic clutch circuit in parallel with mercury switch 77, but also opening the circuit 30 of the solenoid 71. The core piece 72 and stem 73 are now free to drop back down, thus also opening switch 77 and such action may be expedited by providing a check valve in piston 76 as indicated by the ball 79, which rests on top of 35 an opening in said piston.

To those acquainted with this art it will be obvious, that the electro-magnetic switch Q is not necessary, and that the motor M may take its place, when it is not necessary that the motor 40 keep running while the mutoscope wheel stands still in order to expose a card for a certain period of time. When the switches 63 and 77 are thus connected into the motor circuit instead of the circuit of clutch Q, the apparatus functions in 45 exactly the same manner but no ventilation is provided while the mutoscope wheel stands still. If the period of standing still is short, no harm can occur; but if the still picture is to be exposed for a longer period of time it is advisable to use 50 the clutch and thus to keep the fan going.

In the manner of all the other showings of the drawings, the suggestion of the use of the matting 62 is merely exemplary and other means 55 may be used in order to select certain cards for a longer exposure.

For instance I may substitute the arrangement applied to card 80 shown in Fig. 6. The said card is notched as the other cards, in order to clear the finger 60. But a folded strip 81 of sheet metal for instance, is clipped over the outer edge of the card and may be retained thereon by a depressed tooth 82. Such a clip will engage upon the finger 60 in the same manner as the matting 62.

Although I have shown and described one form of embodiment of my invention in detail, yet I do not wish to be limited thereby, except as to the state of the art and the appended claims may require, for it is obvious that various modifications and changes may be made in the form of embodiment of my invention, without departing from the spirit and scope thereof.

What I claim is:—

75 1. In a mutoscope, a frame, a mutoscope card

wheel, a gear on said frame driving said wheel, a driving means, a worm shaft driven by said means, extending therefrom and swingable into mesh with said wheel, a rotatable collar on the free end of said shaft, a hook hinged upon said frame and said collar, said worm shaft being out of mesh with said gear when depending at its free end from said hook, a solenoid, a stem depending from said collar, and a core piece on said stem, lifting said stem when said solenoid is excited 10 and swinging said shaft from said depending position into a position of mesh with said gear, said collar being swung around the point at which it is hingedly depended from said hook into a position substantially above said point. 15

2. In a mutoscope, a frame, a mutoscope card wheel, a gear on said frame driving said wheel, driving means, a worm shaft driven by said means, extending therefrom and swingable into mesh with said wheel, a rotatable collar, on the 20 free end of said shaft, a hook hinged upon said frame and said collar, said worm shaft being out of mesh with said gear when depending at its free end from said hook, a solenoid, a stem depending from said collar, and a core piece on said stem, lifting said stem when said solenoid is excited and swinging said shaft from said depending position into a position of mesh with said gear, said collar being swung around the point at which it is hingedly depended from said hook 30 into a position substantially above said point, a vertical slot being provided in said stem where it engages on said collar, so that said stem and corepiece drop for a predetermined distance before engaging and pulling down said collar, when 35 said solenoid is deenergized.

3. In combination with a mutoscope card wheel, an electrically actuated drive for said wheel, an electrically actuated timing mechanism, a circuit breaking means operatively engaged by some 40 cards of said wheel, and alternately closing the electric circuit of said drive or the electric circuit of said timing mechanism, and a second circuit breaker operatively connected with said mechanism and connected in parallel with said first 45 circuit breaker into the electric circuit of said drive.

4. In a mutoscope the combination with a rotation of cards of substantially like size, a flicking tool, and means cyclically moving said cards past said tool and flicking them thereover, of a plurality of oversize cards and protruding therefrom, and of a device controlling said means arranged next to said rotation of cards, interposed in the path of movement of the parts of said oversize cards protruding from said rotation of 55 cards, and operated when engaged by said protruding parts.

5. In a mutoscope, a rotation of cards, a flipping tool, an electric motor moving said cards and flipping them over said tool, a pair of switches connected in parallel and controlling said motor, a timing mechanism controlling one of said switches and closing it a predetermined time after it has been actuated, and means in connection with one of said cards actuating said timing mechanism 65 and opening the other one of said switches.

6. In a mutoscope, notched and unnotched cards, means moving said cards, a tool flicking said moved cards, and a control device for said means protruding into the notches of but cleared 70 by said notched cards and a clip attachable at will to one of said cards, bridging the notch of said cards and predeterminedly actuating said device when said card moves into a predetermined position.

7. In a mutoscope, a frame, a mutoscope card wheel, a gear on said frame driving said wheel, a driving means, a worm shaft driven by said means, extending therefrom and swingable into mesh with said wheel, a rotatable collar on the free end of said shaft, a hook hinged upon said frame and said collar, said worm shaft being out of mesh with said gear when depending at its free end from said hook, a solenoid, a stem depending from said collar, and a core piece on said stem, lifting said stem when said solenoid is excited and swinging said shaft from said de-
- pending position into a position of mesh with said gear, said collar being swung around the point at which it is hingedly depended from said hook into a position substantially above said point, vertical play being provided for between said stem and its point of lifting engagement upon said collar, so that said stem and core piece drop for a predetermined distance before engaging and pulling down said collar, when said solenoid is deenergized. 5 10

WILLIAM RABKIN.
